UNITED STATES PATENT OFFICE.

DOLPHUS M. TOLTON, OF POMONA, CALIFORNIA.

DISPLAY-PANEL.

1,391,349.

Specification of Letters Patent. Patented Sept. 20, 1921.

Application filed February 23, 1921. Serial No. 447,309.

To all whom it may concern:

Be it known that I, DOLPHUS M. TOLTON, a citizen of the United States, residing at Pomona, in the county of Los Angeles and 5 State of California, have invented certain new and useful Improvements in Display-Panels, of which the following is a specification.

This invention relates to means for displaying advertisements and the like in barber shops and similar places, the principal object of the invention being to provide means whereby the advertisements or other display medium may be seen while a person 10 is reclining in the barber's chair so that he can read and observe the advertisements while being shaved.

Another object of the invention is to provide simple and effective means for supporting the advertisements or other display medium without detracting or marring the walls of the shop.

A still further object of the invention is to provide means whereby the advertisements 25 can be read in the usual side wall mirror when a person is sitting upright.

This invention also consists in certain other features of construction and in the combination and arrangement of the several 30 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view illustrating one unit 40 of the panel in use.

Fig. 2 is an enlarged face view of the panel.

Fig. 3 is a view illustrating the assembled device.

Fig. 4 is a view taken at right angles to Fig. 3.

Fig. 5 is an enlarged face view of the assembled device.

Fig. 6 is a horizontal sectional view 50 thereof.

Fig. 7 is an enlarged sectional view of the assembled panel.

Fig. 8 is a detail perspective view of the reflector section.

55 In these views 1 indicates a panel which is formed of a sheet of suitable material

having a central opening 2 therein with the portions of the sheet bordering said opening bent outwardly to form the holding flanges 3. Small ears or lugs 4 are also 60 formed from the sheet and bent rearwardly to form supporting means for the back sheet 5 against which the sheet 6 containing the advertisements or the like rests. A sheet 7 of glass or other transparent material rests upon the sheet 6 and has its edges 65 engaging the flanges 3. Thus the backing and the sheet containing the advertisements and the glass plate are held in the panel by the flanges 3 and the lugs 4. 70

This panel containing the advertising matter is adapted to be placed on the ceiling A of a barber shop or the like so that when a person is reclining in the chair B he can observe and read the advertisements on the 75 panel while the barber is shaving him. Thus his mind will be occupied so that the time required for the shave will pass quickly and at the same time the articles and merchandise being referred to in the advertisements will be brought to his attention. 80

The panel can be secured to the ceiling in any desired manner and where a metal ceiling is used the panel can be applied thereto. 85

In order to permit the advertisements to be read by a person sitting in upright position in the chair I provide means for reflecting the advertisement into the ordinary side wall mirror C which is placed upon the 90 wall in front of the chair. Such means consists of a frame 8 supporting a mirror 9 and having lugs 10 formed at its upper edge which are bent at right angles and passed through holes 11 in one of the flanges 3 of 95 the main panel. Ears 11' are struck from said lugs 10 and bent at right angles to engage the outer face of the flange 3. These parts are so arranged that the mirror and its frame 8 will be held in inclined position, as 100 shown in the drawings, so that it will reflect the advertising matter carried by the main panel into the side-wall mirror so that a person sitting in the barber's chair can read said advertising matter. 105

I may place a mirror in the main panel in addition to the advertising matter so that the customer can observe himself being shaved.

While the device is mainly designed for 110 barber shops it will of course be understood that it may be used in other shops or places

where a person spends some time in a reclining position.

It is thought from the foregoing description that the advantages and novel features 5 of my invention will be readily apparent.

I desire it to be understood that I may make changes in the construction and in the combination and arrangement of the several parts, provided that such changes fall 10 within the scope of the appended claims.

What I claim is:—

1. A device of the class described comprising a panel made in the shape of a frame, means for supporting an object in the frame, said panel having sockets in one side thereof and a mirror frame having projections thereon for engaging said sockets for holding the mirror frame in an inclined position relative to the panel. 15

2. Means for displaying advertisements 20

in a barber shop comprising a panel made in the shape of a frame for holding the advertisement, means for securing the panel upon the ceiling above the chair, and a mirror frame connected with the panel so as to 25 reflect the advertising matter in the panel into a mirror on the side wall in front of the chair.

3. A device of the class described comprising a panel having bent up flanges 30 thereon for supporting a sheet containing advertising matter, a frame containing a mirror, means for supporting the mirror frame in an inclined position from the panel, such means consisting of projections 35 on the mirror frame and openings in the panel for receiving the projections.

In testimony whereof I affix my signature.

DOLPHUS M. TOLTON.
